Primary Examiner — Ricky Pham(57) **CLAIM**

The ornamental design for a silicone folding warming board, as shown and described.

DESCRIPTION

FIG. 1 is a front, top and right-side perspective view of the silicone folding warming board showing my new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof; and,
 FIG. 8 is a back, bottom and left-side perspective view thereof.

1 Claim, 8 Drawing Sheets(56)
